UNITED STATES PATENT OFFICE.

JOHN J. McGUCKIN, OF WORCESTER, MASSACHUSETTS, ASSIGNOR TO STEVENS WALDEN-WORCESTER, INCORPORATED, OF WORCESTER, MASSACHUSETTS, A CORPORATION OF MASSACHUSETTS.

WHEEL PULLER.

Application filed March 12, 1927. Serial No. 174,866.

The invention relates to devices for pulling wheels or other members from axles or shafts on which they are mounted, in cases in which they have been originally mounted on the shaft with a drive fit or, for any other reason, are difficult to remove. More particularly, the invention relates to that type of puller in which a threaded ring, separate from the main body of the puller, is employed.

The object of the invention is to provide a puller of the type above specified, in which the ring may be first screwed onto the hub of the wheel gear, or other object that is to be removed from a shaft, and the body of the puller then placed over the ring and fixed in position for pulling. According to the invention, the threaded ring provides peripheral recesses and projections, and a member carried by the body of the puller, or a portion thereof formed integral with it, provides interlocking internal recesses and projections. Thus the body portion of the puller may be slipped over the ring which is already in position on the hub, and then turned slightly to lock it in position. The wheel may now be removed by the use of a threaded bolt which reacts against the shaft, or a driving wedge, or any other known equivalent, may be employed as my invention relates to the interlocking ring, and the interlocking member that coacts with it.

The above will be more particularly described in connection with the accompanying drawings, in which—

Fig. 1 is a front elevation of the puller, showing the ring in interlocking position.

Fig. 2 is a longitudinal sectional view on the line 2—2 of Fig. 1.

Fig. 3 is a perspective view of the puller, the ring being removed.

Fig. 4 is a perspective view of the ring, this figure being drawn on a larger scale than Fig. 3.

Like reference characters refer to like parts throughout the drawings.

Referring first to Fig. 2, the body of the puller is shown at 1. As indicated in this figure, the body portion 1 is cup shaped and provides an axial hole 2 therethrough. It also provides a cylindrical recess 3 of a larger diameter than the hole 2, which leaves an internal shoulder 4 for a purpose to be

described. The body portion 1 is externally threaded at 5 and a member 6 is screwed onto it; this member can be fastened in any position of adjustment by means of a set screw 7.

Referring now to Fig. 3, the member 6 provides a plurality of inwardly projecting portions 8 leaving a plurality of recesses 9. The sectional view of Fig. 2 is taken through the projecting portions 8, and it will be observed from said figure that each portion 8 is bevelled as shown at 10. The threaded ring 11 is best shown in Fig. 4; it provides a plurality of projecting portions 12 and recesses 13, the former having bevelled edges 14. The ring 11 is split at 15 and provides internal threads 16.

Referring now to Figs. 1 and 2, a nut 17 is provided which removably fits in the recess 3. A bolt 18, which is threaded as shown, passes through the hole 2 and through the nut 17. Pins 19, 19, located in the cylindrical recess 3 and extending into drilled holes in the body portion 1, prevent the nut 17 from turning when the bolt is turned. A pin 20 extending forwardly from the body portion 1 provides a limiting stop for the ring 11, engaging with the side of one of the projecting portions 12 when the ring is turned.

A plurality of rings 11 are preferably provided, each ring having the same outer peripheral size and shape, but each ring having a different internal diameter to fit different sized hubs. A ring 11 having been selected that fits the threads on the hub of the wheel or other article to be removed, it is screwed onto such hub. Assuming that the remainder of the puller has been assembled substantially as shown in Fig. 3, it may readily be slipped over the ring 11, as the projections 12 will pass through the recesses 9 in the member 6. When the member 6 has thus passed over the ring 11, the latter having come in contact with the body portion 1, the body 1 and the member 6 are rotated until the side of one of the projections 12 strikes the pin 20. The projections 12 are now behind the projections 8.

To remove the wheel, all that is now necessary is to turn the bolt 18. The front end 105 of the bolt eventually contacts with the shaft on which the wheel is mounted, and further turning removes the wheel. If

necessary a blow can be given to the head of the bolt 18 without fear of stripping any threads, since the nut can always move forward in the recess 3. As the turning of the bolt 18 pushes it against the shaft, the reaction on the nut 17 is taken by the shoulder, which draws the body 1 to the right, Fig. 2, this in turn drawing the member 6 in the same direction, forcing the bevelled portions 10 against the bevelled portions 14 of the ring 11, which tightens the ring on the threaded hub by diminishing the size of the split opening 15. This very effectively prevents stripping the threads either of the ring 11 or of the hub.

It should be noted that once the member 6 is properly adjusted on the body portion 1, the relative position of these parts never has to be changed, the only necessary adjustment of the device thereafter consisting in the adjustment of the position of the bolt 18 in the nut 17. The parts 6 and 1 are made separate merely for manufacturing reasons.

I claim,

1. In apparatus of the class described, a split ring, alternate projecting and recessed portions on the outer periphery of said ring,

and there being bevelled edges on said projecting portions, in combination with a hollow member, alternate projecting and recessed portions in the internal periphery of said hollow member, and there being bevelled edges on said projecting portions, whereby said ring and said member may be interlocked together with said bevelled edges in engagement.

2. In apparatus of the class described, a split ring, alternate projecting and recessed portions on the outer periphery of said ring, and there being bevelled edges on said projecting portions, in combination with a hollow member, alternate projecting and recessed portions in the internal periphery of said hollow member, there being bevelled edges on said projecting portions, and nut and bolt means for causing a reacting thrust on said hollow member, whereby said ring and said member may be interlocked together with said bevelled edges in engagement and the said thrust will compress the said split ring.

Dated March 9, 1927.

JOHN J. McGUCKIN.
